(57) **CLAIM**

The ornamental design for footwear, as shown and described.

DESCRIPTION

FIG. 1 is an inner side view of footwear showing our new design;

FIG. 2 is an outer side view thereof;

FIG. 3 is a front view thereof;

FIG. 4 is a back view thereof;

FIG. 5 is a bottom view thereof;

FIG. 6 is a top view thereof; and,

FIG. 7 is a front perspective view thereof.

The broken line showing of the tread pattern of the sole is for illustrative purposes only and forms no part of the claimed design.
